UNITED STATES PATENT OFFICE.

NATHAN RUBENSTEIN, OF NEW YORK, N. Y.

APPARATUS FOR REMOVING WALL-PAPER.

1,208,215.

Specification of Letters Patent.

Patented Dec. 12, 1916.

Application filed March 4, 1916. Serial No. 82,046.

To all whom it may concern:

Be it known that I, NATHAN RUBENSTEIN, a citizen of the United States, and a resident of New York, borough of Bronx, in the county of Bronx and State of New York, have made and invented certain new and useful Improvements in Apparatus for Removing Wall-Paper, of which the following is a specification.

10 My invention relates to an apparatus for removing wall paper.

It is an object of the present invention to provide an apparatus for removing paper from walls in a quick and expeditious manner, and, with the apparatus so arranged and designed, that it may be easily and conveniently carried about, and capable of removing large areas of paper from walls or ceiling with the consumption of but a small quantity of fuel.

20 A further object is to provide an apparatus for removing paper from walls or ceilings utilizing both the moisture and heating properties of steam, and in such manner that but a small quantity of steam escapes; the majority of the steam condensing and returning to the boiler, so that a relatively small boiler may be used without requiring the continual supplying of water to the boiler.

25 A further object is to provide a steam applicator, which, upon contacting with wall paper or other surfaces, will immediately heat and moisten the same, and in a uniform manner; this end being attained with an economical amount of steam consumption, rendering unnecessary the use of a large steam boiler, or the employment of considerable quantities of the fuel.

30 A further object is to provide an apparatus which may be economically constructed, and may be handled with rapidity and despatch, and, with these and other objects in view, which will appear as the description proceeds, my invention resides in the combination and arrangement of parts, and in the details of construction hereinafter described and claimed; it being understood that changes in the precise embodiment of the invention can be made within the scope of what is claimed, without departing from the spirit thereof.

The preferred embodiment of my inven-

tion is disclosed in the accompanying drawings, wherein:

55

Figure 1 is a view in perspective of my wall paper removing apparatus, illustrating the same in actual use; Fig. 2 is a view in front elevation, and partially in section, of the plant for generating and supplying steam to the applicator; Fig. 3 is a view in front elevation of the applicator, portions thereof being removed to illustrate certain details of construction; Fig. 4 is a view in horizontal section, taken on the line 4—4 of Fig. 3.

Referring specifically to the several views, the apparatus is formed with a boiler 10, to which is secured the handle 11 whereby the boiler is rendered conveniently portable. A 70 stove or heating member 12, capable of burning kerosene or other fuel, is mounted below the boiler 10 by the upright supports 13. A water glass 14 serves to indicate the level of the water within the boiler, which supply 75 may be replenished from time to time through the valve 15, which also acts as an escapement for the steam should it be so desired. The return manifold 16 is also carried by the boiler, and communicates therewith through the check valve 17, the latter allowing the return of water to the boiler but preventing the escapement of water therefrom.

Communicating with the top of the 85 boiler is the outlet pipe 18, with which communicates a pressure gage 19, so that the pressure within the boiler may be regulated and maintained at the desired amount. A condensing chamber 20 is carried by the 90 outlet pipe 18, providing that dry steam will enter the steam supply pipe 21, which latter is provided with the regulating valve 22. The outlet supply pipe 21 extends down within the steam separating chamber 20, so 95 that dry steam will be supplied to the flexible conduit 23, which forms a part of the steam supply pipe.

The applicator disclosed in detail in Figs. 3 and 4 comprises a substantial rectangular 100 box 24 formed from sheet metal, the outer edge of which is flared or outwardly turned to form a flange 25. The front wall of the box 26 is locked to the flange 25 and is offset inwardly therefrom so as to lie in a plane 105 to the rear of the flange 25. A removable

frame 27 is seated within the recess or chamber formed by the inward offsetting of the front wall 26 of the box, which frame carries a screen or netting 28 and a pad 29, the latter being formed of material similar to a Turkish towel or other similar article. This pad 29 extends over and is secured to the frame 27 and also projects in front of the plane of the flange 25 of the box so that when 10 the applicator is held against a wall, the padding alone contacts therewith.

Communicating with the interior of the box 24 is the inlet pipe 30 which extends well up within the box and is provided with an 15 inlet valve 31, the latter being connected to the steam separator 20 by the flexible conduit 23. A second and outlet pipe 32 communicates with the interior of the box 24, and is adapted to return the water of condensation from the applicator to the return manifold 16 by the flexible return conduit 33. The front wall 26 of the box is provided with several small outlet ducts 34, through 20 which a limited amount of steam is allowed 25 to escape, maintaining the entire pad 29 moist. The outlet ducts are of such restricted size that a pressure is maintained within the boiler, maintaining the applicator at a high temperature, and the pad 29 highly heated. This heated and moist condition 30 of the pad quickly loosens the paper from the wall, and allows it to be easily removed. A large heating and radiating surface is provided by the front wall 26 of the box, 35 while the screen 27 provides a suitable space for the circulation of steam to the rear of the pad, and also incorporates a certain resiliency therein.

The handle 35 is secured to the rear of 40 the applicator, and allows the entire apparatus to be conveniently used. The restricted openings in the applicator, whereby the pad is maintained in a moist condition, results in the economical consumption of 45 steam, and also requires but a small quan-

tity of fuel for the operation of the apparatus.

What I claim is:—

1. A wall paper remover comprising a closed shallow box, a handle carried thereby, a pad stretched over the front wall of said box, said front wall provided with a limited number of restricted openings communicating with the interior of said box and terminating at the rear surface of said pad. 55

2. A wall paper remover comprising a portable closed box, a handle carried thereby, a pad extending over the front wall of said box, the front wall of said box provided with a limited number of fine openings 60 therein, preventing the rapid escapement of steam from said box, to thereby provide for the maintenance of pressure therein.

3. A wall paper remover comprising a portable closed shallow box with an inwardly offset front wall, a frame including a netting, and a pad, located within the recess defined by the offset front wall, the front wall of said box provided with openings therein. 65

4. A wall paper remover comprising a portable closed shallow box with an inwardly offset front wall, flexible steam inlet and outlet pipes communicating with said box, a frame including a pad, and a 75 netting, positioned within the receptacle defined by the offset front wall, said pad extending substantially flush with the outer edge of said box, the front wall of said box provided with a limited number of restricted 80 openings extending therethrough.

Signed at New York borough of Manhattan in the county of New York and State of New York this 3rd day of March A. D. 1916.

NATHAN RUBENSTEIN.
